(57) **CLAIM**

The ornamental design for a skateboard wheel retainer, as shown and described.

DESCRIPTION

FIG. 1 is a front perspective view of the form 1 of a skateboard wheel retainer, showing my new design;

FIG. 2 is a rear perspective view of the form 1 thereof;

FIG. 3 is a front view of the form 1 thereof;

FIG. 4 is a rear view of the form 1 thereof;

FIG. 5 is a left side view of the form 1 thereof;

FIG. 6 is a right side view of the form 1 thereof;

FIG. 7 is a top view of the form 1 thereof;

FIG. 8 is a bottom view of the form 1 thereof;

FIG. 9 is a state diagram of the form 1 thereof;

FIG. 10 is a front perspective view of the form 2 thereof;

FIG. 11 is a rear perspective view of the form 2 thereof;

FIG. 12 is a front view of the form 2 thereof;

FIG. 13 is a rear view of the form 2 thereof;

FIG. 14 is a left side view of the form 2 thereof;

FIG. 15 is a right side view of the form 2 thereof;

FIG. 16 is a top view of the form 2 thereof;

FIG. 17 is a bottom view of the form 2 thereof; and,

FIG. 18 is a state diagram of the form 1.

The broken lines in the drawings illustrate the portions of the skateboard wheel retainer, which form no part of the claimed design.

1 Claim, 18 Drawing Sheets
